UNITED STATES PATENT OFFICE.

JAMES W. ROOKWOOD, OF JERICO, ASSIGNOR TO JOHN W. DAVIS, OF JERICO SPRINGS, MISSOURI.

HAME-TUG.

SPECIFICATION forming part of Letters Patent No. 516,404, dated March 13, 1894.

Application filed September 20, 1893. Serial No. 485,971. (No model.)

To all whom it may concern:

Be it known that I, JAMES W. ROOKWOOD, of Jerico, in the county of Cedar and State of Missouri, have invented a new and Improved 5 Hame-Tug, of which the following is a full, clear, and exact description.

My invention relates to improvements in harnesses, and especially to hame tugs; and the object of my invention is to produce a 10 hame tug which may be conveniently applied to any hame in ordinary use, is adapted for either single or double harnesses, has means for longitudinal adjustment, which means does not include the puncturing of any portion 15 of the tug so as to decrease its strength, which is also provided with means for adjusting the trace thereon without having holes in the trace, and which is adapted to connect with and be adjusted vertically on 20 the back band of the harness, to the end that it may be easily suited to horses of all sizes.

To this end my invention consists of certain features of construction and combinations of parts, as will be hereinafter described 25 and claimed.

Reference is to be had to the accompanying drawings forming a part of this specification, in which similar figures of reference indicate corresponding parts in all the views.

30 Figure 1 is a perspective view of the hame tug embodying my invention. Fig. 2 is a longitudinal section of the same. Fig. 3 is a cross section on the line 3—3 of Fig. 2; and Fig. 4 is a detail perspective view of the fastening head which is riveted or otherwise secured to the harness trace and is adapted to engage the hame tug.

The body 10 of the hame tug is elongated, as shown clearly in Figs. 1 and 2, and it is provided on its back side with a plate 11, preferably of leather, as this side comes next the horse, which plate is firmly secured to the body 10 and has its ends preferably attached to the body by rivets 12. The body 10 is also 45 firmly fastened to the back plate 11 by straps 13 which extend transversely across the body through grooves 14 in its face and are firmly fastened at the ends to the plate 11. The front end of the hame tug terminates in a 50 fork 15 between the members of which is held the strap 16, adapted to connect with the

hame, and for this purpose the free end of the strap is provided with a strong eye 17 which engages the usual hook or drawbar of the hame. The strap 16 connects with the 55 forked ends of the tug body by means of a bolt 18 which extends transversely through an eye 19 at the rear end of the strap, and the members of the fork are provided with a series of holes 20, so that the bolt 18 may be 60 placed in either pair of holes and the tug may thus be longitudinally adjusted and the means of adjustment does not materially weaken it. The free ends of the members of the fork 15 are connected by a cross bar 21, 65 which strengthens the fork and also serves as a guide for the strap 16. The free end of the body 10, that is, the end opposite to that to which the strap 16 is secured, terminates in a guide loop or keeper 22, through which 70 the harness trace 22^a extends, and this end of the body 10 is slotted transversely, as shown at 23, to receive the back band of a harness. A leaf 24 is hinged, as shown at 25, so as to swing across the slot 23, and on the 75 inner side of the leaf 24 is a tongue 26 which is adapted to engage the perforations of the back band. The body 10 is provided at intervals with holes 27 which are preferably 80 rectangular and these are widened next the back plate 11, as shown at 28 in Figs. 2 and 3. These holes are intended to receive the fastening head 29 of the trace 22^a, which head is firmly riveted to the trace, having a shank 30 which lies flatwise on the trace and 85 through which the rivets pass. The shank is bent at a right angle to form the bolt 31 which extends through the holes 27 and this bolt has on opposite sides flanges 32 which are adapted to project into the recesses 28 and 90 which, when in this position, prevent the removal of the head 29 and the consequent detaching of the trace. The holes 27 are longer than they are wide, and consequently the flanges 32 may be inserted by first turning 95 them into line with the holes, after which they are turned around in the recesses 28 so as to lock the head 29 and trace 22^a to the hame tug. It will be observed that the head 29 may be fastened in either of the holes 27 100 and in this way the trace may be adjusted, and it is not necessary to punch holes in the

trace as is the case where the trace is used in connection with the ordinary buckle, and hence the trace, when arranged as described, is much stronger than usual.

Having thus described my invention, I claim as new and desire to secure by Letters Patent—

1. In a hame tug, the combination with a body provided with a transverse slot, of a leaf hinged to the body and provided with a tongue projecting into the slot, and a trace head secured to the body in front of the slot thereof, whereby the leaf will be held closed by the trace substantially as described.

2. The herein described hame tug, consisting of an apertured and slotted body having

a keeper at one end and a fork at its other end, the members of the fork being provided with a plurality of apertures, a back plate secured to the body a strap adapted to be secured to a hame and adjustably secured between the forks of the body, by a bolt passing through an eye in the strap and the apertures of the members of the fork a hinged leaf provided with a tongue projecting into the slot of the body, and a trace head provided with a bolt fitting in the apertures of the body, as set forth.

JAMES W. ROOKWOOD.
